[57] CLAIM

The ornamental design for a connector for a single strut
mine roof truss, substantially as shown.

DESCRIPTION

FIG. 1 is a bottom, front isometric view of a connector
for a single strut mine roof truss showing my new de-
sign;

FIG. 2 is a bottom, rear isometric view thereof;

FIG. 3 is a left end elevational view thereof;

FIG. 4 is a right end elevational view thereof;

FIG. 5 is a top plan view thereof;

FIG. 6 is a bottom plan view thereof;

FIG. 7 is a front elevational view thereof; and

FIG. 8 is a sectional view taken in the direction of the
arrows on line 8—8 of FIG. 1.
